UNITED STATES PATENT OFFICE.

JONAS NORTHRUP, OF HOPEDALE, MASSACHUSETTS, ASSIGNOR TO HOPEDALE MANUFACTURING COMPANY, OF MILFORD, MASSACHUSETTS, A CORPORATION OF MASSACHUSETTS.

THREAD-PARTER MECHANISM.

Application filed May 26, 1917. Serial No. 171,130.

To all whom it may concern:

Be it known that I, JONAS NORTHRUP, a citizen of the United States, residing at Hopedale, in the county of Worcester and 5 State of Massachusetts, have invented certain new and useful Improvements in Thread-Parting Mechanisms; and I do hereby declare the following to be a full, clear, and exact description of the invention, such 10 as will enable others skilled in the art to which it appertains to make and use the same.

The present invention relates to an improvement in thread parting mechanisms for 15 looms.

The object of the invention is to produce a thread parting mechanism of such construction and arrangement of parts that any filling end extending outwardly from the selvage for a substantial distance will be engaged and severed relatively close to the 20 selvage. To the accomplishment of this object and such other objects as shall herein-after appear the present invention consists 25 in the improved thread parting mechanism described in the following specification and particularly pointed out in the appended claims.

The preferred form in which it is contemplated embodying the invention is illustrated in the accompanying drawings, in which Figure 1 is a perspective view of a portion of a loom showing the application of the improved thread parting mechanism thereto; Fig. 2 is a plan of the parts shown in Fig. 1; and Fig. 3 is a diagrammatic view showing the improved thread parting mechanism located beside each selvage.

The loom in connection with which it is proposed to use the thread parting mechanism of the present invention may be of any usual or preferred type, and may be either a plain loom or an automatic weft replenishing loom. The portions of the loom shown in the drawings for the purpose of illustrating the application of the thread parting mechanism thereto, comprise weaving devices which include a lay 5 which beats up toward the breast beam 6 in order 45 that the reed 7 may press the weft or filling thread 8 against the fell 9, and then beats back or returns in order that the shuttle

may leave another thread in the shed 10. The usual temples 11 are secured to the breast beam 6 to keep the woven cloth 12 55 stretched taut laterally. These parts are familiar to those skilled in the art and perform their usual functions.

The improved thread parting mechanism comprises a horizontally disposed elongated 60 thread support 14 which is arranged along beside the selvage or outer threads of the warp 15 and substantially parallel with or slightly below the plane of the woven cloth 12, or the unraised section 16 of the warp 65 threads. This thread support 14 extends forwardly beyond the fell 9, and rearwardly to the limit of the rearward movement of the lay, and its arrangement is such that any filling end of substantial length extending 70 outwardly from the selvage will be supported in position to be acted on and severed by a thread parter located between the thread support 14 and the selvage. For convenience of illustration, the usual temple cutter 75 18 is shown for performing the thread severing operation. So far as is known, it has not heretofore been proposed to provide means for severing close to the selvage all filling ends extending outwardly from the 80 selvage. The difficulty has been to support the filling end in position to be acted upon by the thread parting means. It is known, of course, that it has been proposed to support in various ways the outgoing filling end 85 extending from the selvage to the critically exhausted bobbin (but only in feeler looms), and the incoming filling end extending from the hopper to the selvage, so that they may be severed close to the selvage; but so far 90 as is known, however, all these prior devices are adapted only for action upon outgoing and incoming filling ends, and cannot act on adventitious filling ends extending beyond the selvage.

The thread support 14 is conveniently supported at its forward end by the loom temple, and at its rear end by an arc-shaped piece 19 which gives forward slightly when the lay strikes the temple. The piece 19 is 100 supported by a rod 20 adjustably secured, longitudinally of the lay, in a bracket 21 fastened to the loom frame. For the purpose of preventing a filling end resting on

the thread support 14 from being whipped out of thread severing position by the draught created by the lay in its backward and forward movements, a thread guard 23 is provided, which is also supported at its forward end by the temple, and at its rear end by the resilient piece 19, as shown in Fig. 1. It will be observed that the thread support 14 and the thread guard 23 approach quite closely together opposite the fell and may aptly be said to constitute a false shed. This arrangement aids materially in keeping the filling end in position to be acted on by the thread parter. It will also be observed that at their rear ends the thread support and the thread guard are separated a distance somewhat greater than the depth of the shuttle, and are so arranged that the shuttle may pass freely between them. The thread support 14, the thread guard 23 and the piece 19 are all constructed of resilient material so that in case the shuttle should stop between these parts, no breakage will result on the subsequent beating up of the lay.

The great advantage resulting from the present construction of thread parter mechanism lies in the fact that all filling ends extending outwardly from the selvage are severed close to the selvage, whether these filling ends are the outgoing and incoming filling ends or whether they are left by the shuttle when the filling therein entirely exhausts or breaks. This fact makes it possible to locate the thread parter mechanism on the side of the loom opposite to that on which the weft replenishing mechanism, indicated at 24, is located. So far as is known, it has not heretofore been proposed to locate a thread parter mechanism on the side of the loom opposite to that on which the weft replenishing mechanism is located. The advantage of this arrangement is obvious. If the filling entirely exhausts or breaks on the flight of the shuttle toward this side of the loom, and a filling end is left extending outwardly from the selvage, this filling end will be severed close to the selvage. The same advantage holds when the thread parter mechanism is located on the replenishing side of the loom, because in that case also, if the filling entirely exhausts or breaks on the flight of the shuttle toward the replenishing mechanism and the filling end extends beyond the selvage, it will be severed close to the selvage. This has not been possible heretofore, because the thread parter mechanisms usually located on the weft replenishing side of the loom are not adapted to act upon a filling end left by a completely exhausted shuttle, unless perchance the filling end is long enough to extend to the shuttle.

It will be understood from the foregoing description that the thread parter mechanism

of the present invention is equally applicable to both plain and automatic looms, and to both filling feeler controlled and filling detector controlled replenishing looms.

Having thus described the invention, what I claim is:

1. A thread parter mechanism for looms having, in combination, a thread support located close to the selvage and substantially in the plane thereof, said thread support extending from the fell rearwardly a distance substantially equal to the length of the throw of the lay, and a thread parter located between the selvage and the thread support.

2. A thread parter mechanism for looms having, in combination, a thread parter for severing the filling ends supported in position alongside of and close to the selvage of the cloth being woven, and a thread support located immediately adjacent to the parter, and therefore located close to the selvage, for supporting, in a position to be engaged and severed by the parter, the filling ends extending outwardly an appreciable distance from the selvage.

3. A thread parter mechanism for looms having, in combination, a thread support, a stationary thread guard, said members being relatively close together opposite the fell and relatively far apart at the limit of the rearward movement of the lay and being arranged so that the shuttle passes between them in its flight, and a thread parter to cooperate with the thread support and the thread guard to sever a filling end extending outwardly from the selvage.

4. A thread parter mechanism for looms having, in combination, a thread parter for severing the filling ends close to the selvage, and thread supporting means for supporting the filling ends in a position to be engaged by the thread parter, said thread supporting means being positioned in such proximity to the selvage that the flexural strength of the filling ends supported thereby will permit them to be loosely supported in a substantially horizontal position.

5. A thread parter mechanism for looms having, in combination, a thread support arranged to support a filling end extending outwardly from the selvage, a stationary thread guard arranged above the thread support to prevent the filling end from being displaced, said support and guard extending between the dents of the reed, and a thread parter to sever the filling end close to the selvage.

6. A thread parter mechanism for looms having, in combination, a thread support and a thread guard mounted on a stationary part of the loom, located beside the selvage and arranged for the passage of the shuttle between them, and having substantially the same relation to each other as the upper and

lower sections of warp threads have when the shed is open, and a thread parter located between the thread support and the selvage.

7. A thread parter mechanism for looms having, in combination, a thread support and a thread guard, angularly arranged with relation to each other and so that the shuttle may pass between them, means adjustable longitudinally of the lay for supporting the thread support and the thread guard, and a thread parter.

8. A loom having, in combination, weaving devices, a thread parter for severing the filling ends supported in position alongside of and close to both selvages of the cloth being woven, and a thread support located immediately adjacent to each parter, and therefore located close to the selvages, for supporting, in a position to be engaged and severed by the parter, the filling ends extending outwardly an appreciable distance from the selvages.

9. In an automatic filling replenishing loom comprising transferring mechanism and means for parting the filling end leading to the filling carrier to be discharged; guiding means permanently anchored to opposite sides of the loom frame at opposite sides of the path of the lay and extending across the lay during its entire beat-up above the path of the filling and operating to direct the filling end into the field of the parting means upon transfer.

10. In an automatic filling replenishing loom comprising transferring mechanism and means for parting the filling end leading to the filling carrier to be discharged; guiding means permanently anchored to opposite sides of the loom frame at opposite sides of the path of the lay and extending across the lay both above and beneath the

path of the filling and operating to direct the filling end into the field of the parting means upon transfer.

11. In an automatic filling replenishing loom comprising transferring mechanism and means for parting the filling end leading to the filling carrier to be discharged; guiding means for the filling end comprising a wire permanently secured to the frame of the loom at opposite sides of the path of the lay and extending transversely across the lay and operating to guide the filling end into the field of the parting means upon transfer.

12. In an automatic filling replenishing loom comprising transferring mechanism and means for parting the filling end leading to the filling carrier to be discharged; yieldable guiding means permanently anchored to the loom frame at opposite sides of the path of the lay and extending across the lay beneath the path of the filling end and operating to direct the filling end into the jaws of the filling end parting means.

13. A loom having, in combination, weaving devices including a lay, a temple thread parter, and a supporting member secured upon the temple and extended transversely across the lay, said supporting member being adapted to support short filling ends extended laterally from the selvage to facilitate the severance thereof by the temple thread parter.

14. A loom having, in combination, weaving devices, a thread parter mechanism located close to one selvage and a false shed located close to the selvage and comprising two members arranged in the planes of the open shed to permit the passage of the shuttle therebetween.

JONAS NORTHRUP.
